WICK FOR DISTILLATE BURNERS

Ernest C. Leach, West Peabody, Mass., assignor
to Lynn Products Company, Lynn, Mass., a
corporation of Massachusetts

Application April 26, 1938, Serial No. 204,279

3 Claims. (Cl. 67—69)

The present invention relates to wicks which are used in distillate burners to draw by capillary attraction oil from the grooves thereof, the oil thus drawn to the top edges of the wicks being 5 burned to bring the adjacent parts of the burner to a temperature at which the main body of the oil in the grooves, and the adjacent supply therefore, is vaporized or gasified, the wicks, upon the firing of the produced vapor or gas, having no 10 further function until such time as it is desired to restart the burner.

It has been proposed heretofore to form wicks for distillate burners out of one or more pieces cut from a roll of tape produced from an absorbent, non-combustible material such as asbestos, the piece or pieces being inserted in the grooves, each piece standing upon one of its longitudinal edges. These wicks, while needed to start the burner, reduce the efficiency of the burner during 20 its normal operation, in that the wicks obstruct the free flow of gas along the bottom of the burner groove, and the induced flow of the gas upwardly through the groove under the influence of the ascending air currents. These wicks are 25 furthermore objectionable in that the tops or unsupported edges thereof tend to droop and become lodged under the adjacent burner sleeves, the cause of a very unsatisfactory fire. Heretofore, it was considered necessary that the asbestos tape 30 from which the wick was formed should be narrow, in order that the wick, when inserted upstanding in the burner groove, would not reach as high as the shoulder upon which the burner sleeve is supported, and should be thin, in order 35 that the wick would allow clearance for the free flow of gas through the groove. But these limitations in the size of the wick reduced the area of the burning surface at and adjacent to its top edge, thus delaying the time in which the 40 burner was heated to the distillate vaporizing temperature. It is well known that the quicker the burner can be heated to the vaporizing temperature, the quicker the burner reaches its condition of normal operation. Because of its 45 quicker starting property, a single, all around cylindrical wick is preferred over several pieces of shorter length, although the multiple piece wick does not obstruct the free flow of gas in the grooves like the one-piece cylindrical wick, 50 which is additionally disadvantageous owing to the lack of satisfactory means for connecting the free ends thereof, or for holding in the groove in a predetermined position.

The principal object of the present invention is 55 to produce a starting wick for distillate burners

which will obviate the objectionable features of the wicks heretofore devised and which will decrease the time in which the burner is heated to the distillate vaporizing temperature.

To the accomplishment of this object, and such others as may appear hereinafter, the various features of the present invention reside in certain devices, combinations and arrangement of parts hereinafter described and then set forth broadly and in detail in the appended claims, which 10 possess advantages readily apparent to those skilled in the art.

The various features of the present invention will be understood readily from an inspection of the accompanying drawings illustrating the best 15 form of the invention at present devised, in which,

Figure 1 is a detail view in plan of a distillate burner of the type disclosed in the patent to Johnson, Reissue No. 18,464, reissued May 17, 20 1932;

Fig. 2 is a detail view in sectional elevation on the line 2—2, Fig. 1;

Fig. 3 is a detail view in plan of the wick;

Fig. 4 is a detail view in sectional elevation 25 on the line 4—4, Fig. 3;

Fig. 5 is a detail view in plan illustrating the manner in which the cut ends of the tape from which the wick is formed is bent into a cylindrical form by the reinforcing strip when the 30 opposite ends thereof are overlapped, and

Fig. 6 is a detail view in elevation of the tape from which the wick is formed, illustrating the manner in which the reinforcing strip is run through the hem woven into one longitudinal 35 edge of the tape.

In the embodiment of the invention illustrated in the drawings, the asbestos tape 7 from which the wick is formed is provided along one longitudinal edge 8 with a hem 9 which is woven integrally into the body portion of the tape at the time the hem is formed, a method to be preferred over forming the hem and securing it to the body portion of the tape by stitches or staples. Sufficient lengths of tape are cut from 45 a roll, (not shown), to form the wicks for the inner and outer grooves 10 and 11 of a distillate burner 12, characterizing features of which are illustrated in Figs. 1 and 2.

The lengths of tape cut from the roll may be 50 bent in the manner illustrated in Fig. 5 in which position a flat, resilient, metallic strip 13, several inches longer than the length of tape, may be run through the entrance 14 to the internal passage 15 in the hem 9 until the leading end 16 of 55

the strip 13 emerges from the exit 17 to the passage 15, whereupon the leading end of the strip 13 is reinserted into the entrance 14 and overlapped upon the portion of the strip adjacent 5 its trailing edge 18. The cut edges of the tape are then drawn together to form the ring-like wick 19 illustrated in Fig. 3.

If the wick 19 is to constitute the wick for the inner groove 19, (Figs. 1 and 2), openings 20 and 10 21 are formed which register with the conduits 22 and 23 through which the gas flows to the outer groove 11.

With this construction, the strip 13 permits the wick to be adjusted to fit the circumference 15 of the burner groove. The strip 13 holds the outer face of the hem 9 pressed against the adjacent face of the burner groove, thus providing a uniform area all around the groove for the unobstructed flow of gas along the bottom of the 20 groove and upwardly under the action of the usual air currents.

The strip 13 stiffens the upper edge of the wick 19 so that it may be constructed to stand above the adjacent shoulder 24 upon which the 25 burner sleeve 25 rests without danger that the wick may become lodged between the shoulder 24 and the sleeve 25. The height of the wick and the width of the hem 9 creates an extraordinary

large amount of oil burning surface which insures that the burner may be heated quickly to a temperature at which the distillate vaporizes.

What is claimed as new, is:

1. A tape for a distillate burner wick comprising a substantially rectangular, thin body of absorbent, non-combustible material having a hem along at least one longitudinal edge and a stiffener run through the internal passage in the hem. 5

10 2. A tape for a distillate burner wick comprising a substantially rectangular, thin body of absorbent, non-combustible material having a hem along at least one longitudinal edge and a stiffener longer than the tape run through the 15 internal passage in the hem.

20 3. A distillate burner wick comprising a ring formed from a substantially rectangular, thin body of absorbent, non-combustible material having free ends and a hem along at least one 25 longitudinal edge and means for maintaining the free ends in a predetermined relative position comprising a stiffener longer than the tape run through the internal passage in the hem, the opposite ends of the stiffener being overlapped within the hem.

ERNEST C. LEACH.
